Primary Examiner — Ian Simmons*Assistant Examiner* — Ieisha Price(74) *Attorney, Agent, or Firm* — Christopher J. Knors; Moore & Van Allen PLLC(57) **CLAIM**

The ornamental design for an adapter device, as shown and described.

DESCRIPTION

FIG. 1 is a first side view showing an adapter device in accordance with our new design;

FIG. 2 is a second side view thereof, the view rotated 90 degrees relative to the first side view;

FIG. 3 is a third side view thereof, the view rotated 180 degrees relative to the first side view;

FIG. 4 is a forth side view thereof, the view rotated 270 degrees relative to the first side view;

FIG. 5 is a top plan view thereof; and,

FIG. 6 is a bottom plan view thereof.

The broken lines in the drawings illustrate portions of the adapter device and form no part of the claimed design.
